METHOD AND APPARATUS FOR MAKING
CAPSULES BY SUBMERGED FILLING AC-
TION

Robert P. Scherer, Detroit, Mich.

Application October 28, 1935, Serial No. 47,095

9 Claims. (Cl. 18—21)

My invention relates to an improved method and apparatus for forming and filling capsules with a fluid or semi-fluid content. An object is to provide an improved method and apparatus whereby capsules may be rapidly and cheaply filled with accurately measured dosages of a fluid filler content and without wastage of material and as a continuous operation.

Another object is to provide an improved method and apparatus of the character described whereby capsules may be filled with a fluid content as set forth herein and without admission of air into the interior of the capsules to form air bubbles in the content ingredients.

Other objects, advantages, and meritorious features of my improved method apparatus will more fully appear from the following description, appended claims, and accompanying drawings, wherein:

Figure 1 is an elevation partly in section of apparatus embodying my invention and adapted to carry out my improved process.

Fig. 2 is a vertical view partly in section taken at right angles to the view of Fig. 1.

Fig. 3 is a plan partly broken away of the stationary supports for the die rolls.

In carrying out my invention I employ a tank 10 adapted to contain fluid filler content material with which the capsules are to be filled. This tank has a bottom 12 shaped as shown in Fig. 1 and the capsule filler content material stands therein to the level indicated in such figure. A pair of hollow complementary cooperating die rolls 13 are mounted for rotation upon stationary shaft elements 14 and disposed within the tank to rotate together partially submerged below the fluid level. These die rolls are provided with a plurality of peripheral cup shaped recesses or capsule die cavities 16, each of which cavities communicates through a passageway 18 with the interior of the roll, and which are arranged in spaced apart relationship circumferentially and axially of the roll. These die cavities are correspondingly located on the two rolls so as to be brought into registration as shown in Fig. 1 on rotation of the rolls. A ledge 17 encircles each die cavity.

Mechanism is provided for forming and feeding a pair of plastic gelatin bands or strips into submergence into the tank and between the die rolls where the capsules are formed and filled. This mechanism comprises a gelatin tank 22 wherein molten gelatin is maintained at the desired temperature through heating means not shown. This tank has two horizontal discharge

outlet slots one to each of a pair of drums or rolls 24 on which the gelatin is spread and formed by cooling into a band 26. These two bands are led from the two drums 24 into the top of the tank 10 passing under heaters 28 and are directed over the die rolls 12 as shown. Each band closely hugs its die roll due to tension purposely created and the two bands come into juxtaposition between the rolls.

The two shaft elements 14 are similar as are the die rolls and serve as the stationary support over which the roll rotates. Each shaft element is cored out as illustrated providing an axial passageway 30 which communicates through a radial passageway 32 with a circumferential recess 34. This recess is open to the inner surface of the die roll and establishes communication with the inner ends of the die cavity passageways 18. The passageways 30 of the two shaft elements are in communication through a conduit 36 which in turn communicates with a vacuum pump not shown.

Each shaft element is also cored out axially as at 42. The passageway 42 communicates through a lead 44 with peripheral recesses 46. These open to the inner surface of the die roll to establish communication with the die cavities through the passageways 18. The two passageways 42 of the two shafts communicate with each other through a conduit 43 which is open to the atmosphere whereby the recesses 46 of these two shaft elements are opened to the atmosphere.

Motor 40 drives the die rolls through shaft 48, worm 50, and gear 52. Gear 52 together with gear 54 and sprocket 56 is connected by a key 51 to a sleeve 58 rotatably supported upon shaft element 14. Each shaft element 14 is provided with such a sleeve and each sleeve is provided with a flange 60 connected by studs 62 or the like with the die roll to drive the die roll. A gear 54 of the sleeve which is driven directly from the worm drives a corresponding gear 54 on the other sleeve to drive the other sleeve whereby the two die rolls are oppositely driven. A drive chain 64 connects sprocket 56 of sleeve 58 with shaft 23 which carries a drum 24. Each sleeve 58 is provided with a sprocket 56 and the chains which engage these two sprockets cross each other extending in opposite directions to engage oppositely disposed drum shafts 23 as shown in dotted outline in Fig. 1. The drum shafts carry sprockets over which these drive chains travel.

Rotation of the die rolls 12 and the drums 24

55

causes the two gelatin bands 26 to enter the liquid within the tank 10 and pass over the die rolls as shown. As each roll rotates its die cavities 16 are brought into communication with the 5 vacuum recess 34 in its shaft element 14 and that portion of the gelatin band overlying the die cavities is drawn into the die cavities forming cavities or cups in the band. These cups fill with liquid as the strip moves through the liquid 10 within the tank. When two such liquid filled cups are brought into registration, as illustrated in Fig. 1, the bands are urged together by the ridges or flanges 17 which surround the complementary die cavities of the two rolls, and the bands are united together around these liquid 15 filled deformations forming capsules about the fluid content material carried in the two halves thereof. These flanges 17 not only seal the two bands together around the cavities formed therein 20 in forming a capsule about the fluid content of the cavities but also serve to sever the gelatin band surrounding such capsule so that the capsule is releasable from the band.

As the two die rolls rotate following the formation 25 of a capsule in their complementary die cavities, these die cavities are brought into communication with the atmospheric condition 46 of the shaft element 14 and that capsule is thereby released for ejection from the band. The passageways 42 here illustrated as communicating with the atmosphere might communicate with a conventional air pressure pump should such additional pressure prove to be desirable.

Stripper mechanism in the form of a wedge 35 block 66 that is disposed upon one side of the web as shown in Fig. 1 and a stripper roll 68 is arranged on the opposite side of the web and is adapted to rotate counter to the direction of travel of the web as shown to strip the filled 40 capsules 59 from the web depositing them upon a conveyor belt 70 from which they are carried to an elevator 72 to be discharged to a collector pan 74. The stripper roll 68 is driven by a chain 76 from shaft 78, sprockets being provided to effect the drive. The shaft 78 may be driven 45 by the conveyor belt 70 from shaft 80 which in turn may be driven from shaft 82 by suitable intermeshed gears 84 and 86. The shaft 82 is shown in Fig. 2. It is driven by chain drive 88 from shaft 90, suitable chain sprockets being 50 provided. The shaft 90 may be driven by chain 92 from a sprocket on shaft 94 which in turn is driven from the adjacent drum shaft 23 by suitable gears, one of which, 96, is shown in 55 Fig. 2.

The web of gelatin after the formed filled capsules are removed therefrom is withdrawn from the tank over idler rolls 98 and deposited in a receptacle 100. A pair of drag rolls 102 engage the web to effect this movement. These drag 60 rolls are driven by suitable gears from the adjacent drum shaft 23 including gears 104 and 106 and a suitably positioned intervening gear not shown in Fig. 1.

In operation the gelatin strips are withdrawn 65 into the die cavities 16 of the die rolls to form the two halves of the capsule. These halves fill with the liquid filler content and upon continuation of rotation of the rolls are brought into 70 registration as described. The gelatin strips are sealed together around the margins of the filled cavities and while they are submerged. The air is excluded from entering the interior of the capsules due to this submergence. The capsules are 75 completely filled with the liquid filler content

material. The capsule itself is positively formed by means other than the pressure of the liquid filler material itself.

I claim:

1. That method of forming and filling capsules with a liquid filler content comprising submerging a pair of strips of capsule forming material within said liquid filler content and while submerged advancing them along converging paths into juxtaposition, forming corresponding cavities in such strips prior to juxtaposition thereof and while the strips are submerged urging corresponding portions of the strips surrounding said cavities together sealing said portions together thereby forming liquid filled capsules. 10

2. That method of forming and filling capsules with a liquid filler content comprising submerging a pair of strips of capsule forming material within said liquid filler content and while submerged advancing them along converging paths into juxtaposition, applying suction to corresponding selected portions of said strips forming cavities therein prior to the submerged juxtaposition of the strips, advancing said strips while submerged into converging juxtaposition bringing corresponding cavities into submerged registration, urging said strips together surrounding said submerged cavities sealing the same together forming liquid filled capsules, and severing said strips surrounding said capsules and releasing the suction therefrom. 20

3. That method of forming and filling gelatin capsules with a liquid filler content comprising advancing a pair of plastic gelatin strips submerged in the filler content along converging paths into submerged juxtaposition, forming corresponding cavities in the two strips and filling said cavities with the liquid filler content by moving the strips through said liquid, sealing said strips together around the margins of two corresponding filled cavities forming a capsule 35 enclosing the liquid filler content of said two corresponding filled cavities and severing the strips about said capsule. 40

4. That method of forming and filling gelatin capsules with a liquid filler content material comprising advancing a pair of gelatin strips while submerged in the liquid filler content material along converging paths into juxtaposition, applying suction to corresponding areas of said strips to form corresponding cavities therein and maintaining said cavities therein until the strips are brought into submerged juxtaposition, urging and sealing said strips together while submerged along the margins of said corresponding cavities, forming capsules filled with said liquid content material severing said filled capsules from the remaining portion of the strips and releasing the suction therefrom. 50

5. That method of forming and filling gelatin capsules with a liquid filler content material comprising advancing a pair of plastic gelatin strips while submerged in the liquid filler content material along converging paths into juxtaposition, forming corresponding cavities in said strips and maintaining said cavities therein during the submerged advance of said strips into juxtaposition, urging said strips together while submerged along the margins of said cavities with sufficient pressure to seal said margins together forming filled gelatin capsules and with sufficient pressure to substantially sever said filled capsules from the remaining portion of the strips, and applying pressure to said filled capsule bodies to extrude the same from the strips. 65

6. Apparatus for forming and filling capsules with a liquid filler content comprising a liquid filler tank, mechanism operable to advance a pair of strips of capsule forming material along converging paths into juxtaposition within said tank including a pair of die rolls provided with corresponding capsule forming cavities, said rolls being rotatably supported within the tank to urge said strips into submerged juxtaposition between the rolls and with corresponding cavities of the rolls moved into registration sealing the strips together around the margins of said cavities, mechanism operable to establish a suction within corresponding cavities of the rolls drawing corresponding portions of the strips thereinto prior to the juxtaposition of the strips between the rolls.

7. Apparatus for forming and filling capsules with a liquid filler content comprising a liquid filler tank, mechanism operable to advance a pair of strips of capsule forming material along converging paths into juxtaposition within said tank including a pair of die rolls provided with corresponding capsule forming cavities, said rolls being rotatably supported within the tank to urge said strips into submerged juxtaposition between the rolls and with corresponding cavities of the rolls moved into registration sealing the strips together around the margins of said cavities, and severing said strips surrounding the line of sealing thereof together, and mechanism operable to establish suction within said cavities to draw corresponding portions of the strips thereinto prior to the submerged juxtaposition of the strips between the rolls, and mechanism operable thereafter to increase the air pressure within said cavities as the filled sealed capsule bodies are fed from between said die rolls.

8. Apparatus for forming and filling capsules with a liquid filler content comprising a liquid filler tank, mechanism operable to advance a pair of strips of capsule forming material along converging paths into juxtaposition within said tank including a pair of die rolls provided with corresponding capsule forming cavities arranged circumferentially thereof, said rolls supported for

rotation within the tank and adapted to urge said strips together therebetween with corresponding cavities brought into registration sealing the strips together around the margins of said cavities, mechanism operable to establish a suction within corresponding cavities successively as they are moved toward registration, and mechanism operable to release the suction within said cavities following their movement into registration and as the filled capsule bodies are fed from between said die rolls.

9. Apparatus for forming and filling capsules comprising, in combination, a pair of arbors, a pair of die rolls each rotatively mounted on an arbor and arranged in endwise juxtaposition, means for feeding a pair of strips of capsule forming material between said die rolls, means for supplying liquid filler material into the space between said strips of capsule forming material as they are fed between said die rolls, each of said die rolls provided with a plurality of capsule forming cavities on its periphery arranged to advance into registration with corresponding cavities on the other die roll as the die rolls rotate about their respective arbors, each of said die rolls further provided with air passages leading from the base of each cavity to the inner periphery of the die roll, each of said arbors provided with a pair of recesses on their respective peripheries into which said air passages open, means for producing subatmospheric pressure in one recess of each of said arbors, means for producing a relatively greater air pressure in the other recess of each of said arbors, said recesses arranged relative to one another and to said air passages to cause subatmospheric air to enter the cavities of said die rolls as they approach registration and to cause air under greater pressure to enter said cavities as they diverge from registration whereby said strips of capsule forming material are first deformed by the subatmospheric pressure to furnish corresponding halves of filled capsule bodies and then released from said cavities by the increased air pressure supplied thereto.
